H. R. RICARDO

INDUCTION SYSTEM OF INTERNAL COMBUSTION ENGINES

Filed Jan. 12, 1924

FIG. 1.

FIG. 2.

FIG. 3

By Harry R. Ricardo,
Nation, Colt, More & Grindley
Atty's.

UNITED STATES PATENT OFFICE.

HARRY RALPH RICARDO, OF LONDON, ENGLAND.

INDUCTION SYSTEM OF INTERNAL-COMBUSTION ENGINES.

Application filed January 12, 1924. Serial No. 685,786.

To all whom it may concern:

Be it known that I, HARRY RALPH RICARDO, subject of the King of England, and residing at London, in England, have 5 invented certain new and useful Improvements in the Induction Systems of Internal-Combustion Engines, of which the following is a specification.

This invention relates to the induction 10 systems of internal combustion engines and more particularly to the induction systems of four cylinder fourstroke internal combustion engines of the type in which the combustible mixture is supplied to all four cylinders by a single carburettor and in which the inlet ports of all four cylinders are independent of one another.

The object of this invention is to provide 15 an induction system for such engines which will give increased uniformity in the strength of the mixture and the weight of the charge supplied to the several cylinders as compared with that given by known induction systems and which shall give this 20 improved result without recourse to excessive velocities or to excessive heating.

According to this invention two separate 25 and non-communicating induction conduits are provided, each of which extends between the induction ports of two of the cylinders whose inlet valves are actuated so that there 30 are equal time intervals between the successive openings of these ports, and these induction conduits communicate with a single carburettor by means of two pipes branching from above the carburettor, each 35 of these branch pipes opening substantially at right angles into the centre of the length of one of the induction conduits. Preferably 40 the two induction conduits extend as directly as is practicable between the inlet ports with which they communicate and the branch pipes from the carburettor are conveniently at an acute angle to each other.

45 This invention is particularly applicable to vertical four-cylinder engines having cranks in the same plane and at 180° to each other. If, as is usual with such engines, the firing order of the cylinders is 50 1-3-4-2, then the inlet ports of cylinders 1 and 4 and those of 2 and 3 are respectively connected by separate induction conduits in the manner described above, these conduits being conveniently horizontal 55 and communicating with a single carburettor preferably by means of vertical conduits.

Thus if cylinder No. 1 performs its induction stroke and the closing of its inlet valve sets up oscillations in the horizontal induction conduit connecting it with cylinder 60 No. 4, these oscillations do not have any appreciable effect on the combustible mixture in the vertical conduit communicating with the carburettor since the mixture can oscillate freely in the horizontal conduit between cylinders 1 and 4. Still less can these oscillations have any effect on the mixture in the horizontal induction pipe connecting cylinders 2 and 3, so that when cylinder No. 3 performs its induction stroke the mixture 65 drawn in is unaffected by oscillations set up by the closing of the inlet valve of cylinder No. 1.

Further, by the time the induction period of cylinder No. 4 begins such oscillations 70 have to a large extent been damped out, since although cylinder No. 4 draws its combustible mixture from the same induction pipe as cylinder No. 1, there is an appreciable time interval between the closing 75 of the inlet port of cylinder No. 1 and the time when that of cylinder No. 4 opens. Similarly as no two cylinders draw consecutively from the same induction pipe, each 80 cylinder receives a charge unaffected by the closing of the inlet port of the preceding cylinder.

This invention may be carried out in various ways but one arrangement according to this invention is illustrated somewhat 85 diagrammatically in the accompanying drawings in which—

Figure 1 is a horizontal section of an engine having an induction system according to this invention.

Figure 2 is a transverse vertical section of the same engine.

Figure 3 is a side elevation with the crank case broken away showing the arrangement of the cranks.

The engine shown has four cylinders A, B, C, D having separate inlet ports indicated at A', B', C', D'. The cranks L, M, N, O of the engine are in the same plane those of each of the pairs A, B and C, D being at 180° to one another as shown in Figure 3, and the arrangement is such that the firing order of the cylinders is A, C, D, B. The inlet ports in each of the pairs A, D, and B, C, are respectively connected by 105 two entirely separate and substantially horizontal induction pipes E and F which com-

municate with the carburettor G by means of two substantially vertical pipes H and J opening respectively into the induction pipes E and F at right angles thereto and at or 5 about the centres of their lengths. The two pipes H and J merge into a single pipe K just above the carburettor, the angle between the pipes being as illustrated pref-erably acute.

10 The operation of the engine is as follows. Assume that the firing order of the engine is A, C, D, B, for example. Cylinder A performs its induction stroke and on the inlet valve closing the gas column proceeding 15 along the horizontal portion of the manifold E which connects A and D is arrested, and rebounds along this manifold towards cylinder D. As there is every opportunity for the rebounding gas to oscillate freely between cylinders A and D, there is 20 no inducement for the oscillating gas to set up any appreciable disturbance in the vertical branch H from the carburettor which leads into it at right angles. With the firing 25 order under consideration, cylinder C will have commenced its induction stroke before cylinder A has completed its induction stroke, but owing to the fact that cylinders B and C are fed by the manifold F independent 30 from the manifold E which feeds cylinders A and D, the oscillation of the column of gas in the manifold E will not affect, for the reasons already stated, the induction stroke of cylinder C. At the completion 35 of the suction stroke of the cylinder C the rebound of the gas column caused by the shutting of the inlet valve of cylinder C will set up an oscillation of the gas column in the manifold F connecting cylinders B and C, and this oscillation can proceed 40 freely as was the case when describing the suction stroke of cylinder A as the two manifolds are entirely favourable to the free oscillation of columns of gas within them in their horizontal portions without having 45 any inducement or facility for setting up disturbance in the vertical branches H and J which lead into them.

It will be seen that with this arrangement no two cylinders with cranks at 180° draw 50 successively from any one conduit, so that after any one cylinder is filled the flow of gas in that conduit ceases, whereas when one conduit feeds two cylinders with cranks 55 at 180° as in known constructions, the second cylinder receives a richer mixture and a greater weight of charge owing to the velocity set up by the first, for the advantage due to the kinetic energy of the column 60 is reaped only by the second cylinder.

It is to be understood that the arrangement described above may be modified in accordance with the type of engine to which the invention is applied.

65 While especially applicable to four-cylin-

der four-cycle engines it may be utilized with engines having more than four cylinders.

What I claim as my invention and desire to secure by Letters Patent is:—

70 1. In an internal combustion engine operating on the four-stroke cycle and having four cylinders and four separate inlet ports, the combination of two separate and non-communicating induction conduits each of 75 which extends between the induction ports of two cylinders whose inlet valves are actuated so that there are equal time intervals between the successive openings of these ports, a carburettor, and two pipes branching from above the carburettor each branch pipe opening substantially at right angles into the centre of the length of an induction conduit.

76 2. In an internal combustion engine operating on the four-stroke cycle and having four or more cylinders, a plurality of induction conduits each of which connects the intake ports of a plurality of cylinders whose suction strokes do not overlap, a carburettor, and means for conducting gaseous fuel from the carburettor to each of said conduits, said means comprising a conduit having one inlet and a plurality of outlet ports, said conduit being branched remote from said outlet ports which communicate respectively with said induction conduits.

79 3. In an internal combustion engine operating on the four-stroke cycle and having four or more cylinders, a plurality of induction conduits each of which connects the intake ports of a plurality of cylinders whose suction strokes do not overlap, a carburettor, and means for conducting gaseous fuel from the carburettor to each of said conduits, said means comprising a branched conduit having one inlet and a plurality of outlet ports opening respectively into said induction conduits, said conduit freely communicating through its outlet ports with the induction conduits respectively, at points midway of the length of each.

86 4. In an internal combustion engine operating on the four-stroke cycle and having four cylinders and four separate inlet ports, the combination of two separate and non-communicating induction conduits each of 100 which extends between the induction ports of two cylinders whose inlet valves are actuated so that the suction strokes of the cylinders do not overlap, a carburettor, and a conduit leading from the carburettor to the induction conduits said conduit having two branches and each branch opening substantially at right angles into an induction 105 conduit midway of its length.

110 5. In an internal combustion engine operating on the four-stroke cycle and having four cylinders and four separate inlet ports, the combination of two separate and non-

communicating induction conduits each of which extends between the induction ports of two cylinders whose inlet valves are so actuated that there is an appreciable interval between the end of one induction stroke and the beginning of the other, a carburetor, and a conduit leading from the carburetor to the induction conduits said conduit having two branches and each branch opening substantially at right angles into an induction conduit midway of its length. In testimony whereof I have signed my name to this specification.

HARRY RALPH RICARDO.
